J. L. TUTTLE.

Cotton Gin.

No. 15,904.

Patented Oct. 14, 1856.

UNITED STATES PATENT OFFICE.

JNO. L. TUTTLE, OF NEW YORK, N. Y.

IMPROVEMENT IN MANUFACTURING CYLINDERS FOR COTTON-GINS AND MACHINE-CARDS.

Specification forming part of Letters Patent No. 15,904, dated October 14, 1856.

To all whom it may concern:

Be it known that I, JOHN L. TUTTLE, of the city, county, and State of New York, have invented certain new and useful Improvements in the Manner of Making Cylinders for Cotton-Gins, Carding or Cleaning Engines, &c.; and I hereby declare the following to be a full, clear, and exact description of the same, reference being had to the accompanying drawings, making a part thereof, in which—

Figure 1 represents in perspective the inner and outer metallic cases, which compose the body or ground of the cylinder when made. Fig. 2 represents a horizontal section through the several parts of which the cylinder is composed when ready or prepared for the pouring of the metal which unites them.

To enable others skilled in the art to make and use my invention, I will proceed to describe the same by reference to the drawings.

In the first place I prepare a cast-iron block or former of the proper diameter, with jaws or clamps connected to it, so that a piece of sheet-iron of the right length may be bent or clamped around it tightly. This forms the sheet into the cylinder *a*, and while thus held the lapped ends are punched, so as to be afterward riveted, either while on or after it is taken off from the block or former, as seen at *b*, Fig. 1. The block or former may also be provided with rounded grooves or recesses, into which the sheet is pressed to form the gutters *ccc*. After the inner cylinder is thus prepared, as shown in Fig. 1, another plain cylinder, *d*, is formed around it, and fitting as snugly to it as can be conveniently done, by either the same block or former and clamp, or by other similar means, and holes *e* are punched through the outer cylinder, *d*, into the gutters *c*, formed in the inner cylinder. These two cylinders *a* *d* being placed the latter outside of the former, (after they are removed from the block,) rings *f*, first turned true, are placed within the inner cylinder, at suitable distances apart, to keep the cylinder from warping or twisting during the after operation of pouring in the metal. The bed or basis of the toothed cylinder being thus prepared, a paper cylinder, *g*, containing the teeth *h*, is slipped over the outer cylinder, leaving a space, *i*, between the outer cylinder, *d*, and the paper cylinder *g*, into which the teeth *h* project.

The manner of setting the teeth in the paper

cylinder is fully set forth in my patent of October 30, 1849, and need not here be elaborately described.

These several parts above set forth being properly arranged, they are then ready to be soldered or cemented together by hot metal poured in, as will be now described, first remarking that any kind of heat may be applied to the interior of the cylinders to warm or heat the metal, so that the solder or fluid metal poured in shall flow freely all around. The fluid metal is poured in at the tops of the gutters *ccc*, in any of the well-known convenient ways of accomplishing this object, to make the operation as expeditious as possible, and avoid the bad consequence incident to too much haste. The metal thus poured in at *e* runs down the gutters, and through the holes *e* into the space *i*, completely filling up said space, and, uniting the ends of the teeth with itself and the cylinders, forms one rigid mass. The object of thus introducing the fluid metal or solder is this: The teeth having been tinned so that the solder will firmly adhere to them, when the soldering operation is exposed to the air, an oxide of tin forms, which clogs the solder and prevents its certain flow in between and around the roots of the teeth. By my plan the outer cylinder, *d*, protects the solder from the teeth until the solder reaches the holes *e*, and when it has reached that point the mass of solder above *e* not only acts as a head to force it through *e* and around the roots of the teeth, but it protects the soldering process from the atmospheric air, and no oxide can form which would clog the flow of the metal. I thus make a perfectly-formed junction between the teeth and the cylinder, and should the two cylinders *a* *d* not fit to each other exactly, the solder finds its way between them, and thus closes up every crack, orifice, or opening, bringing the whole into one firmly-united mass by a certain and expeditious process. After the cylinder is cooled the paper is soaked off, as described in my former patent, and by introducing a wooden or other head into each of the ends of the cylinder for holding the journals or shaft upon which it is to turn, it is ready for use. During the whole process of heating, pouring, and cooling, the rings *f* keep the cylinders in true circular form, and prevent any undue twisting or warping of the metal.

Having thus fully set forth the character of my invention and shown how it may be reduced to practice, what I claim therein, and desire to secure by Letters Patent, is—

The manner herein described of making cylinders for cotton-gins or for carding or cleaning engines—viz., by introducing the fluid metal which is to unite the teeth to the cylinder between the cylinders *a* *d*, and through

the openings *e* into the space *i*, which unites the whole into one rigid mass, and avoids the danger of irregular flowing of the melted metal—as set forth.

J. L. TUTTLE.
